UNITED STATES PATENT OFFICE.

WILLIAM J. GILBERT, OF CHICAGO, ILLINOIS.

BUILDING TILE.

Application filed August 15, 1921. Serial No. 492,476.

To all whom it may concern:

Be it known that I, WILLIAM J. GILBERT, a citizen of the United States, residing at Chicago, in the county of Cook and State 5 of Illinois, have invented a certain new and useful Improvement in Building Tiles, of which the following is a full, clear, concise, and exact description, reference being had to the accompanying drawings, forming 10 a part of this specification.

This invention relates to building tiles and more particularly to a hollow tile for use in the construction of weight sustaining walls for buildings.

15 It is a purpose of the invention to provide a building tile of ceramic material that is so constructed that mortar can be more readily applied to the faces thereof having openings therein and that is provided with openings so arranged as to key the mortar in the tiles.

20 It is a further purpose of the invention to provide a building tile of the above mentioned character provided with a central, preferably circular, opening to provide an air cell therein, said central opening being surrounded by a series of mortar keying 25 openings arranged thereabout.

It is moreover a purpose of the invention 30 to provide a building tile of unusual strength by making the same of double arch formation with the bases of the arches facing each other.

It is another and further purpose of the 35 invention to provide a building tile so constructed that the density of the material thereof will be substantially uniform throughout. This is accomplished by providing the large central opening whereby 40 the core forming said opening when the clay is forced through a die to form the tile is forced outwardly thus counteracting the tendency of the material to flow more readily in the center of the mass when in 45 a plastic state. Similarly the webs on the outside of the tile are made thicker than inside for the same purpose.

Other objects and advantages of the invention will appear as the description of the accompanying drawing proceeds. However, I desire to have it distinctly understood that I do not intend to limit myself to the exact details shown therein or described in the specification but that I intend 55 to include as part of my invention

all such obvious changes and modifications of parts as would occur to a person skilled in this art and as would fall within the scope of the claims.

In the drawing is shown a perspective 60 view of the hollow building tile.

The improved building tile shown in the drawing is rectangular in form being provided with top and bottom faces 1, side faces 2 and end faces 3, said faces 1, 2 and 3 being in planes at right angles to each other. The building tile is made up of web portions extending longitudinally thereof spaced so as to provide a series of openings. The web structure comprises 70 straight side webs 4, curved web portions 5 and short straight web portions 6 joining said side webs with the curved webs. At the top and bottom of the tile are webs 7 joining the curved webs to the side webs, 75 said webs 7 and said webs 4 being of greater length than the web 6 and the curved web 5. The tile is provided with a central substantially circular opening 8 within the curved web portion extending from end to 80 end of the tile. The opening 8 provides an air cell or air space which will extend throughout a layer of said tile as the openings 8 are aligned when the tiles are laid. The tile is also provided with openings 9 85 between the corners thereof and the central opening, said openings 9 being substantially rectangular in form except for the curved portions adjacent the curved web 5. Between adjacent openings 9 are 90 provided the openings 10, which are narrower than the opening 9, and are substantially rectangular in form.

It will be seen from the drawings that the curved web and the portions 6 form a pair 95 of arch-like members facing each other within the rectangular cell-like portion formed by the webs 7 and 4 to provide great strength for the tile due to such arch formation. The openings 9 and 10 are provided 100 for receiving the mortar to key the mortar to the tile. In the tile, the mortar is butted or laid on the end faces of the tile between the central opening and the side faces 2, so that the same enters the openings 9 and 10 when the opening 8 is left 105 open to provide an air space. A very strong structure is obtained due to the keying of the mortar in the tile, which is practically impossible with the common tile, having 110

rectangular openings, all of which form air spaces and are of enlarged size compared with the openings 9 and 10.

In making tiles of plastic material, the material is forced through a die of a shape to provide the desired shape of tile. Difficulty has been experienced in obtaining a tile of uniform density of material where the same size webs are provided and the same size openings are provided throughout the tile, as the material tends to flow more rapidly through the center of the die than at the edges thereof. It will be evident that with the tile shown, the die will be provided with a circular central core 8 and this core would tend to force the material away from the center of the die, thus causing the flow of the material to be more uniform throughout the area of the die. By making the webs 5 and 6 narrower than the webs 7 and 4 the flow of the material at the outside of the tile is also aided, thus producing a tile of substantially uniform density throughout. This is very important as a tile that is not of uniform density throughout is quite often ruined in the handling thereof in the process of making the same, due to the fact that breakage occurs where there is a variation in density.

Having thus described my invention, what I desire to claim and secure by U. S. Letters Patent is:

1. A building tile of the character de-

scribed comprising rectangular outer wall portions, and inner web portions connected with said outer wall portions, all said inner web portions being thinner than any of said outer wall portions, said webs being arranged so as to provide a large central opening, and smaller side openings, 40 said side openings comprising larger corner openings and smaller intermediate openings.

2. A building tile of the character described comprising rectangular outer wall portions, and inner web portions connected with said outer wall portions, said web portions comprising arcuate web portions defining a large central opening, and parallel web portions connecting the side wall portions of said tile with said arcuate web 50 portions.

3. A building tile of the character described comprising rectangular outer wall portions, and inner web portions connected with said outer wall portions, said web portions comprising arcuate web portions defining a large central opening, and pairs of parallel web portions connecting the side wall portions of said tile with said arcuate web portions, said parallel web portions extending substantially parallel to the top and bottom outer wall portions.

In witness whereof, I hereunto subscribe my name this fourth day of August, A. D. 1921.

WILLIAM J. GILBERT.
